UNITED STATES PATENT OFFICE

2,354,739

SOUND RECORDING MACHINE

Henry P. Clausen, White Plains, N. Y., assignor
to The Gray Manufacturing Company, Hartford, Conn., a corporation of Connecticut

Application April 16, 1943, Serial No. 483,271

8 Claims. (Cl. 179—100.4)

This invention relates to improvements in the sound recording art in relation to the conjoint action of several machines capable of recording sound upon a permanent record tablet or its equivalent.

The main objects of this invention are to provide two or more time recording machines, circuits therefor, and control devices in circuits whereby near the completion of the recording of sound on one machine another machine of the group is automatically set in operation; whereby two or more machines may be simultaneously operated to record the same sounds upon the corresponding number of records; or whereby sound recorded on one machine may be recorded therefrom on one or more other machines.

A further object is to provide in such a system sound reproducing mechanism whereby at the completion of the reproduction of sound from the record of one machine another machine is automatically set in operation to continue the reproduction therefrom.

Other and more detailed objects of this invention will be apparent from the following detailed description of an embodiment thereof.

This invention resides substantially in the combination, construction, arrangement and relative location of parts all as will be described in detail below.

In the accompanying drawing, the single figure is a schematic and diagrammatic illustration of an embodiment of the subject matter comprising the invention disclosed herein.

The subject matter of this invention may be used with sound recording machines of various kinds, but the embodiment herein disclosed will be described in connection with a type of machine which employs a thin flexible disc of some suitable material such as cellulose acetate upon which the record is recorded and from which it may be reproduced. A specific disclosure of a machine of this type will be found in United States Patent No. 2,296,870, issued September 29, 1942, to Proctor and Thiede.

The subject matter of this invention is very well adapted to use in remotely controlled or central station sound recording systems wherein a plurality of machines are located at a central point under the supervision of an attendant. This central station is connected with a plurality of relatively remotely situated dictation stations from which all the necessary signals and controls may be initiated for the purpose of recording dictation of any length without the necessity of the dictator being directly concerned

with the machines and the operations incident to their use.

In accordance with the invention at each dictator's station is a relatively simple control unit including a combined microphone-loud speaker, a signal lamp and a single switch for starting and stopping the machine assigned to the dictator in the usual manner.

The system herein disclosed may be used either as a direct or remote control system for controlling the operation of two or more machines so that recording on one machine is transferred to the next in the series near the end of the record of the former machine, and for a short period of time the same subject matter is recorded on both records so that there is what may be termed overlapping recording during this period. Likewise, with such an arrangement reproduction may be effected successively and automatically from machine to machine, but in the case of reproduction each machine as it initiates reproduction in the next machine immediately interrupts reproduction from itself so that there is no overlapping period during reproduction.

The system is further designed so that the same sounds may be recorded simultaneously on the two or more machines or the record on one machine may be transferred and recorded on two or more other machines.

The sound recording reproducing machine diagrammatically illustrated herein is preferably of the type disclosed in full detail in the above mentioned patent. It consists of a carriage 1 which is supported in any suitable way for rectilinear motion in a radial direction with respect to the sound record tablet 3 which is keyed to the rotatable spindle 2 mounted on the carriage. The record tablet is caused to revolve by engaging a power driven friction wheel 4 from below which wheel in the use of the machine is revolving continuously. Positioned above the wheel 4 is an idler pressure wheel 5 rotatably mounted on a pivotally supported arm 6 so that when the arm moves downwardly from the position shown in Figure 1, the record tablet 3 is gripped between the continuously rotating wheel 4 and the idler wheel 5 with the result that the record 3 revolves, causing the spindle 2 to turn with it. Through suitable connections, not shown, to the spindle 2, the carriage is caused to move slowly in a radial direction from right to left since recording and reproduction begin from a point near the center of the record and proceed outwardly in a spiral path of small pitch to the periphery. In actual use the axes of rotation of the wheels 4 and 5

will be on the plane of the paper, as will be obvious to those skilled in the art. Lever 6 is grounded as shown.

At 7 and 8 are respectively illustrated, in a diagrammatic way, the sound reproducing and sound recording heads which may be of any well known types such as the electromagnetic or the piezo electric crystal types. One terminal of each is grounded and the other terminals are respectively connected to the fixed contact fingers forming part of a switch having the movable support 9. Mounted on this support are the contact fingers 10 and 11 which are respectively connected to the output and input terminals of a suitable amplifier diagrammatically illustrated at 12. This amplifier is preferably of the vacuum tube type and is provided with a signal light 13 energized thereby to give a visible signal to the attendant that it is in good operating condition. This light is preferably of the gas discharge type such as a neon lamp.

At this point it may be noted that the elements comprising machine No. 1 are substantially the same as the elements comprising machine No. 2, and therefore the corresponding parts of the latter have been given the same numbers distinguished however by a prime exponent. A detailed description of machine No. 2 will therefore not be necessary.

A second pair of fixed contacts cooperate with the movable contacts 10 and 11 and are connected by a wire 14 to the working contact of a switch 15 forming part of a relay of which the magnet 25 is the operator. The other terminal of switch 15 is connected by a wire to one terminal of the combination microphone-loud speaker 16, the other terminal of this unit is grounded by the wire 17 and is also connected to the working contact of switch 29. The other contact of this switch is connected to one terminal of switch 27 forming part of relay 25. A switch 18 is arranged to connect ground to one terminal of the magnet 25 and to wire 19, which wire extends to the magnet 20. At this point it will be noted that various magnets have their other terminals connected to the positive side of a current source, not shown for the purpose of simplifying the drawing. Magnet 20 may be called the start-stop magnet. Magnet 25 may be called the latching magnet. These and similar discussions will aid in distinguishing one element from the other in the following description.

The pivoted lever 6 controls a pair of contacts, one of which is connected by wire 21 to a neon signaling lamp 22 at the dictator's station, the other terminal of which is connected to wire 17. The other contact controlled by the lever 6 is connected by a wire to the fixed contact 130 and to the grounded neon lamp 24 positioned at the machine. Switch 130 is of the type which closes upon a very slight pressure and limited movement and is of the type now known as a microswitch. This switch is positioned to be engaged by the carriage 1 when it moves to the left to a point near the end of the recording space on the record tablet 3. The movable contact of this switch is connected by a wire to one terminal of the shifting magnet 30, which includes switches 28, 32, 39 and 40. The working contact of switch 28 is connected by wire 31 to the rest contact of switch 27 of the latching relay 25. The working contact of switch 32 is grounded and the other contact is connected to a heating coil forming part of the thermostatic switch 33 and to the contacts of switches 35 and 36 which are grounded

as shown and forming part of the time delay relay 34. A circuit for the winding of this relay is completed by the thermostatic switch as shown. The working contact of switch 35 is connected to wire 19, the working contact of switch 36 is connected to the working contact of the grounded start switch 38 and to one terminal of the unlatching magnet 37 which operates the latch 28 so that when the latching relay is energized switch 15 closes and switch 27 shifts from its rest to its working contact where they are both held until the unlatching magnet 37 is energized. Switch 39 has its working contact connected to the working contact of a third switch in the switch including the movable support 9. Switch 40 connects ground upon wires 41 and 42 respectively, as shown. Wire 41 runs into wire 19' and really corresponds to wire 19 while wire 42 extends to the start switch 18'. Switches 38 and 38' are called the tripping switches.

Between the pair of machines are provided a pair of key switches 43 and 44. Each of these switches has three positions, that is a neutral position as shown, a clockwise position to control the switches 45 and 46 and a counter-clockwise position to control the switches 48, 49 and 50. These switches are connected as shown. Switch 46 normally short circuits a resistance pad 47 in the lead to the microphone-loud speaker 16.

At the right it will be seen that a number of the circuit wires terminate in arrow heads indicating that by connecting these wires to the next machine in the manner in which machine No. 1 is connected to machine No. 2, a third machine 35 may be added to the series and so on to include as many machines as desired. The only other change noted in adding a third machine would be to shift the wires A from No. 2 machine to No. 3 machine.

A description of the various ways in which this circuit may be operated will now be set forth in detail. It will be assumed that these machines are at a central station and that one or more dictator's stations are situated remotely with respect thereto but connected to the control circuits as illustrated. It will further be assumed that there is an attendant at the central station who takes care of keeping the machine supplied with record tablets and of initiating the operation of the machine, as will be explained. If a person at a dictator's station wishes to record on machine No. 1, for example, he will signal the central station in any suitable manner—although there is nothing shown in the drawing to indicate how this would be done since there are many well known ways to effect such a signal. Assuming that the operator has placed a fresh record disc 3 on the machine 1, has moved the carriage 1 to the extreme right and engaged the recording head 8 with the record tablet near its center, he momentarily closes the start switch 18. It is first to be noted, however, that the power driven wheel 4 will be in operation. The closing of switch 18 completes a circuit for the latching magnet 25 in an obvious manner to close switch 15 and to shift switch 27 to its working contact. The closing of switch 18 also completes a circuit from ground through wire 19 to the start-stop magnet 20. The momentary energization thereof will pull the lever 6 down, causing the idler wheel 5 to grip the top of the record 3. The lever 6 will stay down in this position until the next operation of the start-stop magnet 20. There are a number of well known forms of electro-magnetically operated devices 75 for accomplishing this action, and it is believed

therefore that the diagrammatic illustration is sufficient. The attendant at the time of placing the recording head 8 on the record tablet 3 will throw the support 9 downwardly into recording position so that contact 10 engages the lower adjacent fixed contact, thereby connecting the recording head 8 with the output of the amplifier 12 and contact 11 will move into engagement with the adjacent fixed contact to connect the input of the amplifier 12 to wire 14 and through switch 15 to the unground terminal of the microphone-loud speaker 16. The amplifier 12 being in operation the neon light 13 will be visibly energized to advise the attendant that it is in operating condition.

Returning to the energization of the latching relay 25, it will be seen that switch 27 connects start-stop switch 29 through switch 28 to wire 19, thus placing the start-stop magnet 20 under the control of switch 29. Ground will be connected through lever 6 and wire 24 to one side of the neon light 22, the other side of which is connected to the power source through the start-stop magnet 20. Thus the neon light 22 will be energized to indicate to the dictator that the machine is in operation and ready for his use. The amount of current flowing through the high resistance neon lamp 22 will not be sufficient to operate the magnet 20. The other contact controlled by lever 6 will place ground on neon lamp 24 which will be extinguished until the proper time for its operation. The dictator if he is ready may then begin to dictate, but if he is not ready he momentarily closes switch 29 to stop rotation of the record 3. This is accomplished by establishing a circuit from ground to wire 17 through switch 29, through the working contact of switch 27, through the rest contact of switch 28, through wire 19 and the start-stop magnet 20. The energization of this magnet, lever 6 being down, will cause it to move upwardly relieving the pressure of the idler wheel 5 on the record disc 3 so that this recording machine will stop.

When the dictator is ready to start the machine he again momentarily closes switch 27 completing a circuit to the start-stop magnet 20 to pull lever 6 down. He then speaks into the microphone which is grounded at one terminal so that the impressed currents will flow through closed switch 15, wire 14, switch 11, to the input of amplifier 12, and from the output by way of contact 10 to the wire connected to the recording head 8. Thus the matter to be recorded is impressed upon the record. The dictator may stop whenever he desires by again momentarily closing switch 29. If he continues to dictate until record tablet 3 is substantially full, carriage 1 will by that time have moved to the point where switch 130 is momentarily closed. This energizes the shifting magnet 30 so that all of the switches controlled thereby are closed. The closing of the right hand part of switch 40 will put ground on wire 42 energizing the latching relay 25', causing switch 15' to close and switch 27' to shift to its working contact. The closing of switch 15' puts the microphone on the input of the amplifier 12' through wire 14' and contact 11', the movable support 9' being in recording position. The output of the amplifier is connected through contact 10' to the recording head 8'. Signal lamp 13' is energized apprising the attendant that machine No. 2 is now in use, and therefore indicating to the attendant that machine No. 1 has about used up its record. Of course, the drive wheel 4' is in operation as are the drive wheels of all the

machines normally. The closing of the other part of switch 40 places ground on wire 41 and by it through wire 19' to the start-stop magnet 20' so that the lever 6' moves downwardly to start machine No. 2. Thus the dictated matter will at this period be simultaneously recorded on the record tablets of machine No. 1 and No. 2. The closing of switch 39 on its working contact partially completes a circuit from switch 39 and unlatching relay 37 to the lowermost switch of the support 9, but nothing happens since this switch is open. The closing of switch 32 places ground on the heating coil of the thermostatic switch 33 which at the end of a predetermined interval of time places ground on the magnet 34, closing switches 35 and 36. The closing of switch 35 grounds wire 19 and hence energizes the start-stop magnet 20 to stop machine No. 1. The closing of switch 36 places ground on the unlatching magnet 37 which raises the keeper of latch 36 permitting switch 15 to open and switch 27 to fall back on its resting contact. The time period of the thermostatic switch is adjusted so that the desired amount of overlapped recording will occur after which machine No. 1 stops. With the closing of switch 130, the signal light 24 is energized when arm 6 rises and removes the short circuit apprising the attendant that machine No. 1 has stopped and its record tablet is full. During the period of overlapped recording the start-stop function of switch 29 will be effective only for machine No. 2. This results from the fact that when the shifting magnet is energized, switch 28 sets up a circuit from the switch 29 through the working contact of switch 27, through the working contact of switch 28, through wire 31, through the working contact of switch 27', through the rest contact of switch 28' to wire 19'. Thus during the short period of overlapped recording the closing of switch 29 will stop machine No. 2 and upon the next closing start it again so that the remote dictator has the necessary and full control at all times.

As a result of the above operations machine No. 2 is now recording and machine No. 1 has come to a rest. The attendant may therefore remove the full record disc 3 and replace it by a fresh record, shift the carriage 1 back to the extreme right, and replace the recording head on support 9 in recording position so that the machine is all ready to pick up the recording at the end of the recording on record tablet 3'. Near the end of the recording on tablet 3', micro-switch 130' will be closed to start the next machine in the series with a similar set of operations as described in the transfer from machine No. 1 to machine No. 2. As illustrated machine No. 2 is interconnected with machine No. 1 so that the recording will be transferred back from machine No. 2 to machine No. 1. However, any desired number of additional machines can be included in the series with a connection between the last and the first like that illustrated in the drawing to close, so to speak, the cycle of operations. As illustrated when micro-switch 130' closes the shifting magnet 30' is operated to close, among others, switches 40' so that a circuit is completed back through the wires connected to the wires A to cause the starting of machine No. 1 and the completion of circuits as previously described.

When desired the circuits may be easily set up to cause the simultaneous recording of the same dictation on two or more machines so that two or more records are made when conditions require duplicate recordings. It is, of course, assumed

that fresh records are placed on both machines, that the carriages are at the extreme right, that the power driven friction wheels 4 and 4' are in operation and the recording heads 8 and 8' are in contact with the records. The attendant then operates the key switch 44 by pressing it to the right, which places ground on the left hand pair of contacts 48 to energize the latching relays 25 and 25'. It then throws the same key to the left, leaving it in that position, which closes switches 49 and 50. The key is left in this position to maintain these switches closed. The closing of switch 50 places the start-stop switch 29 at the dictator's station in control of both start-stop magnets 20 and 20' so that the dictator may simultaneously start and stop both machines in accordance with the requirements of his dictation. As before, when the micro-switch 130 of machine No. 1 closes, the shifting relay 30 will operate. At the same time current is supplied through switch 49 to the unlatching magnet 37' and through switch 40 and wire 41 to 20' so that machine No. 2 stops immediately while machine No. 1 does not stop until the thermostatic switch 33 closes. Thus machine No. 1 will remain in operation for a very short period of time after machine No. 2 comes to a stop. However, since the record lines on a machine of this type are so fine as to require about 225 per radial inch, it is apparent that the amount of recording on the two records does not differ very much.

The system may also be used for re-recording which is to say for recording the data on one record onto another record. For example, a full record may be placed in the machine No. 1 and the matter recorded thereon may be impressed upon an empty record mounted in machine No. 2. As before, the machine carriages will be properly set with the proper records on them, but in the case of machine No. 1 the reproducing head 7 will engage the record tablet while the recording head 8' of machine No. 2 will record its record tablet. Whereas the support 9' will be in the downward position for recording the support 9 will be in the upper position for reproduction, in which case contact 11 will engage the contact connected to the reproducing head 7, thus connecting the reproducing head to the input of the amplifier 12. Contact 10, connected to the output of the amplifier, will engage the contact above it to connect the output by wire 14 to switch 15 after preliminary preparation of the machines by the attendant. The attendant operates the key 44 to the right to energize both latching relays 25 and 25' through the switch 48 as previously explained. He then moves the key to the left to close switches 49 and 50 as previously explained. Key No. 43 is then manipulated to the left where it is held in locked position to open switch 46 and remove the short circuit from the resistance pad 47. The resistance 47 is connected in circuit with switch 15 to cut the volume of reproduction from the reproducing head 7 in order that the recording head 8' will not be overloaded. In view of the prior description it is believed that it will not be necessary to detail again the operation of the circuits for re-recording other than that just given.

Key 43 is provided solely for the attendant who when he throws it to the left to place ground on the contacts 45 will operate all the unlatching relays so as to place the machines in their normal inoperative position so that they cannot be used while he is absent. In other words, this control is provided to easily place the machines in normal

inoperative position whenever this condition is desired.

Except in connection with re-recording no mention has been made of reproduction. The operation of the machine for reproduction can readily be seen from the descriptions that have preceded but a little further reference to reproduction may be helpful in fully explaining the system. For example to reproduce from machine No. 1 the attendant will place a full record on the carriage 1, moving the carriage to the right, initiate the operation of the drive wheel 4, shift the support 9 upwardly to connect the recording head to the input of the amplifier and the output of the amplifier to wire 14 and switch 15. He then starts the machine by closing start switch 18 as before, so that the dictator may now hear the recorded matter at the microphone-loud speaker 16. His start-stop switch 29 is in control so that he may start and stop the machine as required. If the dictator wishes to listen to several records in succession, the attendant will also condition machine 3 for reproduction involving the same operations as explained with respect to machine No. 2. When machine No. 1 gets to the position to close micro-switch 130 the shifting magnet 30 will be energized to close all its switches including switch 39 which it will be seen is connected to the lowermost switch on the support 9 which during reproduction is closed. Thus ground is immediately put upon the unlatching relay 37 so that during reproduction machine No. 1 stops instantly upon the closing of micro-switch 130 rather than having a delayed stop through the action of the thermostatic switch 33. At the same time through switch 40 machine No. 2 is started up so that the reproduction continues from this machine with no overlap of reproduction because of the fact that if overlapping occurred the result to the ear would be inarticulate. Thus, reproduction is quite similar to recording except that there is no overlapped operation during reproduction.

An interesting feature of this invention is that a combination of two machines, as illustrated in the single figure, represents what may be termed a unit machine in which the machines may be used singly or in combination for recording and reproduction, all as previously explained in detail. When required, this unit machine may be expanded by the addition of one or more machines by connection to the circuit wires terminating in arrowheads as previously explained. However, the key switches 43 and 44 would not normally be included between each succeeding pair of machines because the unit machine which includes the switches, as illustrated, is capable of handling the additional functions of duplicate recording and re-recording. However, the feature of continuous recording with travel from one machine to the next can be continued on as many machines as a particular situation would require.

From the above detailed description of the operation of the system herein disclosed, it will be apparent that by means of a few manipulations the mechanism may be adapted for continuous recording, continuous reproduction, simultaneous recording on two or more tablets, and re-recording from one to other tablets for duplication purposes. Those skilled in the art will readily appreciate from the above description that many variations may be introduced without departing from the true novel scope of the invention. I do not, therefore, desire to be strictly limited to the disclosure,

but rather by the scope of the claims granted me.

What is claimed is:

1. In a sound recording system the combination comprising at least two recording machines for recording sounds on records, means controlled by each machine for starting another machine when the record of the former is substantially full, means controlled by each machine for stopping it a predetermined period of time after it has started another machine, a dictator's control for starting and stopping an operating machine, and an attendant's control for connecting the dictator's control to two or more machines whereby duplicate records of the same dictation may be made.
2. In the combination of claim 1, means also controlled by each machine for transferring the dictator's control to each machine as it is started by another.
3. In the combination of claim 1, an attendant's control device for rendering all machines inoperative.
4. In the combination of claim 1, an attendant's control device for disabling the dictator's control of said machine.
5. In a system of the type described, the combination comprising a plurality of sound recording and reproducing machines, each machine in-

- 10 cluding a recording head and a reproducing head, means operated by each machine during recording for starting another machine when the record of the former is substantially full, a dictator's control for starting and stopping the operating machine, an attendant's control for causing simultaneous operation of two or more machines whereby the recording head of one machine may be fed by the reproducing head of another to effect re-recording, and means for reducing the current output of the reproducing head during recording to prevent overloading of the recording head.
- 15 6. In the combination of claim 5, an attendant's control device for simultaneously rendering all of said machines inoperative.
- 20 7. In the combination of claim 5, an attendant's control for rendering two or more machines simultaneously operative whereby duplicate recordings may be effected.
- 25 8. In the combination of claim 5, an attendant's control for rendering two or more machines simultaneously operative whereby duplicate recordings may be effected, and for placing the dictator's control in control of the conjointly operating machines.

HENRY P. CLAUSEN.
